UNITED STATES PATENT OFFICE.

DAVID M. SINGER, OF CHICAGO, ILLINOIS.

DESIGN FOR A DISPLAY STAND.

Application filed July 24, 1924. Serial No. 10,246. Term of patent 3½ years.

To all whom it may concern:

Be it known that I, DAVID M. SINGER, a citizen of the United States, residing at 815 West Congress St., Chicago, in the county of Cook and State of Illinois, have invented a new, original, and ornamental Design for a Display Stand, of which the following is a specification, reference being had to the accompanying drawing, forming part thereof.

Figures 1 and 2 respectively, are a perspective and plan view of a display stand showing my new design.

I claim:

The ornamental design for a display stand, as shown.

DAVID M. SINGER.
